US00D575245S

(12) **United States Design Patent**
Yen

(10) **Patent No.:** US D575,245 S
(45) **Date of Patent:** ** Aug. 19, 2008

(54) **MATRIX TYPE LIGHT EMITTING DIODE ASSEMBLY**

(75) Inventor: **Tzu-Hsuan Yen**, Taipei Hsien (TW)

(73) Assignee: **Edison Opto Corporation**, Taipei Hsien (TW)

(**) Term: **14 Years**

(21) Appl. No.: **29/274,438**

(22) Filed: **Apr. 24, 2007**

(51) LOC (8) Cl. **13-03**

(52) U.S. Cl. **D13/180**

(58) **Field of Classification Search** D13/180;
D26/2; 257/79, 80, 81, 88, 89, 95, 98, 99,
257/100; 313/483, 498, 500; 362/555, 800

See application file for complete search history.

(57) **CLAIM**

The ornamental design for a matrix type light emitting diode assembly, as shown and described.

DESCRIPTION

FIG. 1 is a perspective view of a light emitting diode assembly for plane illumination showing our new design thereof;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Wherein the broken lines in the drawings represent unclaimed subject matter.
